UNITED STATES PATENT OFFICE.

HERMAN LUDWIG KRANZ, OF BROOKLYN, NEW YORK.

POCKET TOOL-HOLDER.

1,336,083.

Specification of Letters Patent.

Patented Apr. 6, 1920.

Application filed September 18, 1919. Serial No. 324,427.

To all whom it may concern:

Be it known that I, HERMAN L. KRANZ, citizen of the United States, and resident of Brooklyn, in the county of Kings and

5 State of New York, have invented certain new and useful Improvements in Pocket Tool-Holders, of which the following is a specification.

This invention relates to devices for securely retaining tools, implements, and the like, in the pocket, and has for its object to provide such a device which is simple in construction, inexpensive in cost of manufacture, and readily insertible into the pocket 15 of the carrier of the tool, implement, or the like.

The above and other objects will become apparent in the description below, in which characters of reference refer to like-named 20 parts on the drawings, of which—

Figure 1 represents a front elevational view of my device with a rule retained thereby for the purposes of illustration.

Fig. 2 represents a side elevational view 25 of my device.

Fig. 3 represents a sectional view of my device taken on the line A—A of Fig. 2.

Fig. 4 represents a view illustrating the utility of my device in practice.

30 Referring now in detail to the drawings, my device comprises a main frame constructed preferably of a continuous or endless wire 1 bent into the configuration illustrated, so as to form a mouth-like holder

35 having two legs 2 and 3. Thus my device is of a substantially U-shaped appearance in front elevation, and of an inverted substantially U-shaped appearance in side elevation. A sheet-metal wing 4 is stretched be-

40 tween each pair of opposite members of the frame 1, and is folded back and securely clamped as at 5, without the aid of rivets or other binding means. It is apparent that the jaws 4 of the mouth of my device are flexible,

45 and may be readily separated so as to clamp a tool or the like between them and thus retain the same. Likewise it is apparent that the opposite legs 2 and 3 are flexible, and may be readily separated or brought

50 nearer to each other. This latter property is availed of in my device; I insert the same into the pocket, the legs 2 and 3 first, holding the same pressed toward each other, and then, when the same are in the pocket,

55 I release the pressure on them, allowing them

to separate, whence they are forced against the interior of the pocket, preventing the device from falling out or even from forceful removal.

Having the device then in the pocket, the rule, or tool, or implement, is inserted between the jaws 4, which give way and then securely clamp and retain the said rule or the like, preventing it from falling out or even from forceful withdrawal by a thief. 60

I slit the wings 4 as at 7, and insert the ends of a patch of cloth or felt, or the like 6, through said slits from the inside, said felt being stretched so as to provide a smooth, soft surface. The purpose of this 70 is to provide a smooth surface for contact with the rule or other article, so that the same will not be scratched or otherwise injured or marked. The use of my device is indicated in Fig. 4, which shows a rule 8 75 held in my device between the jaws 4, and the legs 2 and 3 secured in the pocket 9 of a mechanic's overalls.

It is obvious that my invention supplies a much-needed want, as most mechanics 80 have experienced the inconvenience of having their rules or tools drop from their pockets, particularly without their knowledge. With my device such accidents are impossible, and likewise theft of a rule or 85 tool from the pocket is also impossible.

Having thus described my invention, what I claim and desire to secure by Letters Patent is as follows:

1. In a device of the class described, 90 means for retaining a tool, implement, or the like comprising an endless wire bent into a pair of substantially U-shaped jaws, said wire also providing a pair of mutually divergent legs for securing the device in the 95 pocket, said jaws and legs being resilient, said jaws also being mutually divergent, each jaw having a band of sheet metal or the like extending over the same, and felt or the like on said bands for providing a 100 smooth surface upon which said tool, implement, or the like is adapted to slide on insertion into or removal from said device.

2. In a device of the class described, means for retaining a tool, implement, or the like, 105 comprising a pair of mutually divergent jaws and a pair of mutually divergent legs, and a body portion joining said jaw and leg portions, all formed of an endless resilient wire, said jaws being mutually divergent in 110

a direction at right angles to the direction of divergency of said legs, and means for guiding said tool, implement, or the like into said device consisting of a band of sheet metal or the like stretched across each jaw, and a smooth surface inside each jaw composed of a piece of felt or the like, said

bands having parallel slots therein through which said felt or the like passes and is thereby retained in said bands.

10

Signed at New York in the county of Kings and State of New York this 5th day of September A. D. 1919.

HERMAN LUDWIG KRANZ.
